(57) CLAIM

The ornamental design for a faucet body, as shown and described.

DESCRIPTION

FIG. 1 is a top plan view of the faucet body of the present invention showing my new design with the phantom lines depicting environmental structure and forming no part of the claimed design;

FIG. 2 is a left side elevational view thereof with the phantom lines depicting environmental structure and forming no part of the claimed design;

FIG. 3 is a front elevational view thereof;

FIG. 4 is a bottom plan view thereof;

FIG. 5 is a right side elevational view thereof; and,

FIG. 6 is a rear elevational view thereof.
